(57) **CLAIM**

The ornamental design for an electronic access control device, as shown and described.

DESCRIPTION

FIG. 1 is a perspective view of an electronic access control device;

FIG. 2 is a front view thereof;

FIG. 3 is a top view thereof;

FIG. 4 is a bottom view thereof;

FIG. 5 is a left side view thereof; and,

FIG. 6 is a right side view thereof.

A rear view of the electronic access control device is flat and devoid of surface ornamentation, and therefore is omitted. The broken lines are included for the purpose of illustration of portions of the electronic access control device that form no part of the claimed design.
